(57) **CLAIM**

The ornamental design for a folding cart, as shown and described.

DESCRIPTION

FIG. 1 is a front, top perspective view of a folding cart, showing my new design;
FIG. 2 is a rear, bottom perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof;
FIG. 8 is a bottom plan view thereof;
FIG. 9 is another perspective view of the folding cart, shown in an alternative position;
FIG. 10 is another perspective view thereof, shown in an alternative position; and,
FIG. 11 is an enlarged view of detail "11" identified in FIG. 1.

The dashed broken lines in the figures illustrate portions of the folding cart that form no part of the claimed design. The dash dot dash broken lines in FIGS. 1 and 11 are for the purpose of illustrating the enlarged view indicators and form no part of the claimed design.
